US00D955248S

(12) **United States Design Patent** (10) **Patent No.:** **US D955,248 S**
(45) **Date of Patent:** **** Jun. 21, 2022**

(54) **PLUG FOR TESTING BUILDING PIPEWORK**

(71) Applicants: **Bruce Kimberley**, Berowra (AU); **Ian Kimberley**, Hornsby (AU)

(72) Inventors: **Bruce Kimberley**, Berowra (AU); **Ian Kimberley**, Hornsby (AU)

(**) Term: **15 Years**

(21) Appl. No.: **29/715,740**

(22) Filed: **Dec. 4, 2019**

(30) **Foreign Application Priority Data**

Jun. 14, 2019 (AU) 201913314

(51) **LOC (13) Cl.** **10-05**

(52) **U.S. Cl.** **D10/96**

(57) **CLAIM**

We claim the ornamental design for a plug for testing building pipework, as shown and described.

DESCRIPTION

FIG. 1 is a top view of a plug for testing building pipework; FIG. 2 is a side view of the plug for testing building pipework shown in FIG. 1;

FIG. 3 is a bottom view of the plug for testing building pipework shown in FIG. 1;

FIG. 4 is a front view of the plug for testing building pipework shown in FIG. 1;

FIG. 5 is a rear view of the plug for testing building pipework shown in FIG. 1;

FIG. 6 is a front perspective view of the plug for testing building pipework shown in FIG. 1; and,

FIG. 7 is a rear perspective view of the plug for testing building pipework shown in FIG. 1.

1 Claim, 2 Drawing Sheets
